COMBINED SWITCHBOARD AND MESSAGE CENTER DESK UNIT

Richard H. Wann, P.O. Box 514, Barrington Heights, Ill.

Filed July 8, 1964, Ser. No. 80,761

Term of patent 14 years

(Cl. D26—14)

FIG. 1

FIG. 2

FIG. 3

FIG. 4

FIG. 5

FIG. 1 is a perspective view of a combined switchboard and message center desk unit, showing my new design; FIG. 2 is a right end elevational view; FIG. 3 is a top plan view; FIG. 4 is a left end elevational view; and FIG. 5 is a rear elevational view thereof.

I claim:

The ornamental design for a combined switchboard and message center desk unit, substantially as shown.
